UNITED STATES PATENT OFFICE.

CHARLES O. ERICSON, OF HELMETTA, NEW JERSEY.

MACHINE FOR PUTTING COVERS ON CANS.

Application filed June 27, 1925. Serial No. 39,985.

My invention relates to improvements in machines for putting covers on cans, and the general object of my invention is to produce a practical machine which will automatically place the covers on filled cans and press the covers firmly to place. More particularly my invention is intended to produce a machine through which filled cans may be fed one behind the other, to provide means for shaping the cans so as to make them true and in condition to receive the covers, to automatically apply the covers to the individual cans while they are held in shape ready to receive the covers, and then to push the cover firmly to its seat.

My invention also is intended to produce a machine which will work with great rapidity, and to this end I provide a hopper into which the covers may be dumped loosely, and have means for automatically raising these covers or lids to a chute which delivers them to the cans, and further provide means for automatically placing these covers right side up in the chute through which they are fed. Furthermore, to provide means for maintaining a constant supply of covers right side up in the delivery chute, and for returning the covers which are wrong side up, and which are in excess of the number required, to the supply hopper. My invention is also intended to provide means for accurately and resiliently guiding the individual covers to the appropriate cans, and placing the covers on at one edge and then gradually placing the whole cover over the can top by the movement of the can through the machine. These and other advantages will appear from the description which follows.

Reference is to be had to the accompanying drawing forming a part of this specification, in which similar reference characters indicate corresponding parts in all the views.

Figure 1 is a plan view of the machine embodying my invention.

Figure 2 is a broken end view thereof, partly in section.

Figure 3 is an end view of the opposite end to that shown in Figure 2.

Figure 4 is a side elevation of the machine.

Figure 5 is an elevation partly in section taken from the side opposite to that shown in Figure 4.

Figure 6 is a detail showing the means for finally pressing the covers to place.

Figure 7 is a broken enlarged detail plan of the part of the machine where the cover is applied to the can.

Figure 8 is a broken enlarged side elevation of the part of the machine shown in Figure 7.

Figure 9 is a vertical section on the line line 9—9 of Figure 7.

Figure 10 is a vertical section on the line x—x of Figure 7 looking in the direction of the arrows 10, and

Figure 11 is a cross section on the line x—x of Figure 7 looking in the direction of the arrow 11.

The drawings are made from a machine which is in actual operation putting covers on cans filled with snuff, but it will be understood that many details of the machine may be changed without affecting the invention, and that it can be readily adapted to cans of other shapes and kinds.

As shown in the drawings, the machine is provided with a frame 10 which can be of any approved design, and at one end is a conveyor for carrying the cans into and through the machine, which is in the form of a belt 11, the upper member of which runs over a support 12 in a common manner, and the belt conveyor is carried by pulleys 13 and 14. Above the upper member of the belt are spaced guides 15 preferably of angle iron, which are spaced apart so as to guide the cans 16 in a row through the machine. The belt can be driven in any suitable way, but in order that the invention may be clear, I have shown driving mechanism in which the shaft 17 of the pulley 13 is provided with a pulley 18, and the shaft 19 of the pulley 14 is mounted in suitable bearings on the end of the machine (see Figure 4). The pulley 18 which is preferably in the form of a sprocket wheel, connects by a chain 18' with the sprocket wheel 20 on the shaft 21, and the latter connects by pinions 22 and 23 with the driving shaft 24 which extends lengthwise of the machine (see Figures 1 and 4) and is provided with driving means which in the present instance comprises a pulley 25 and belt 26. Thus the carrier or belt 11 is constantly driven through the means described, or equivalent means, and the cans 16 which have been filled, are placed on the belt

100
105
110

so as to be carried through the machine. The cans can be placed in any convenient way, as for instance by hand, or as is customary in analogous machines the cans may be delivered from a filling machine directly upon the carrier 11, and as remarked, they are guided and kept in line by the spaced guides 15.

As the cans progress and come to the point where the covers are to be applied, they are of course open, and may be somewhat distorted in shape. To be sure that the cans are symmetrically shaped so as to properly receive the covers, they are at this point engaged by the rotating shaping wheels 27 and 27' (see Figures 1, 8 and 10) which have spaced recesses 28 shaped to fit half around the can, and as the shaping wheels are opposed, the opposite and registering recesses 28 will close around each can as it passes between the arms of the wheel, and give it its proper form ready to receive the cover. To facilitate this operation, a pair of similar wheels 29-29' are arranged on the same shafts as the wheels 27-27', but are placed below so as to engage the can sides lower down. Cans of the kind shown in the drawings are usually provided with beads 16' near the top, and therefore the backs of the recesses 28 are grooved as shown at 30 (see Figure 8) so as to fit over these beads without distorting the can. These members 27 and 29 can be rotated in any convenient way, and I have shown parallel shafts 31 which are spaced apart and vertically arranged in the machine frame, the shafts being arranged to turn in unison, and the most convenient way is to connect them by gears 32 (see Figure 3). One of the shafts 31 is driven, and as shown in Figure 3 this shaft is provided with a worm gear 33 connecting with a worm 34 (see Figure 6) on a counter shaft 35 which is hung in suitable bearings 36 and is arranged parallel with the driving shaft 24. This shaft is provided with a conventional slip clutch 37, so that in case of too much resistance the clutch will slip without damaging any connected parts, and the shaft can be driven in any suitable way, as for instance by the pulley 38, belt 39, and pulley 40 on the shaft 24.

Covers for the cans are supplied from a hopper 41, which has preferably a screen bottom 42 (see Figure 1) to permit dust and dirt to rattle through, and into this hopper the covers 43 are dumped promiscuously. These covers it will be noted are in the present instance of a dish shape so as to fit nicely over the can top, but both the cans and covers might be of different shapes, in which case anyone familiar with the art would understand shaping the parts which fit the can and cover correspondingly.

65 The covers are raised from the hopper 41

by a continuous carrier 44 which can most conveniently be a belt having cleats 45 thereon, and I have shown the belt carried at its upper end by a pulley 46, and at the lower end by a pulley 47 (see Figures 70 2 and 3). The belt or carrier 44 enters the hopper 41 through an opening 48 (see Figures 1 and 2), and the upper member runs parallel with the wall of the hopper which serves as a support for the belt. 75 After it leaves the hopper, the belt passes through the guide chute 49 to prevent the covers which it carries from being split.

It will be noticed by reference to Figure 5 that the chute 49 is considerably wider 80 than the carrier belt 44, and therefore I arrange guides 50 and 51 alongside the belt, the guide 50 extending substantially parallel with the belt and just above its surface, so as to guide the covers 43 to a 85 central position thereof, while the guide 51 extends inward across the belt and is spaced therefrom so that a cover which lies flat will pass beneath the member 51, but if it is cocked, or rides on another, it will be 90 engaged by the member 51 and pushed off into the chute 49 so as to be returned to the hopper. The upper end of the carrier together with its pulley, is supported by the pulley shaft 52 which turns in hangers 53, 95 and these serve as supports for this part of the mechanism, including the chutes and hoppers presently described. The lower pulley 47 of the carrier 44 is secured to a shaft 54 (see Figure 3) which is mounted 100 in suitable bearings 55 on the hopper 41, and has a sprocket wheel 56 driven by a chain 57 connecting with a sprocket wheel 57' (see Figure 1) on the driving shaft 24.

The covers in the hopper 41 must be kept 105 agitated and moved about so that a sufficient number of them will fall on the carrier 44, and a convenient and efficient form of agitator is shown in Figures 1 and 5, comprising belts 58 which are arranged on each side 110 of the carrier 44 and parallel therewith, these belts passing through holes 59 and 60 in the wall of the hopper 41 and running over pulleys 61 and 62 (see Figure 3), one of the pulley shafts 63 being driven by 115 means of a sprocket wheel 64 and chain belt 65 connecting with a sprocket wheel 66 on the shaft 54 already referred to. As these belts 58 are constantly running, they keep the covers in the hopper agitated, and a 120 sufficient number of them will fall on the carrier 44 to keep the latter fairly well filled, and in practice it is completely filled.

The capacity of the carrier 44 is much 125 greater than is necessary to supply covers to the cans as they pass through the machine, because many of the covers have to be returned to the hopper on account of their disarrangement, or being wrong side up, as will presently appear.

As the covers pass over the upper end of the carrier (see Figure 5) some of them will be bottom side up and some will be top side up. Those that are bottom side up are blown off laterally by a jet 67 through which a current of air passes into the wide flat mouth 68 (see Figure 3) of the delivery chute 69, passing into said chute bottom side up, and the chute is of such a height that they cannot turn over. The chute however is given a bend 69' (see Figure 5), so that as the covers are discharged from the lower end of the chute to be pressed on the cans, they will be top side up. It is important that the chute 69 be loaded, and so more than a sufficient supply is delivered from the carrier 44 to the mouth of the chute, but to provide for this excess without clogging the machine, the receiving end portion of the chute has a side opening 69^b (see Figure 1), delivering into the hopper 72, which connects by a pipe 73 with the pipe 71, and this delivers into the hopper 41. When the chute 69 is filled up to the opening 69^b, the excess covers will roll off through the opening, but the chute will be kept full to this point. The pipe 71 also connects with a hopper 70 which is in line with the pulley 46 and the upper end of the carrier 44, so that the covers 43 which are top side up as they pass over the top of the carrier, will not be blown into the mouth 68 but will pass over and fall into the hopper 70 and so back to the hopper 41. Thus it will be seen that I provide a positive means, thoroughly automatic, for keeping the hopper 69 loaded with covers in sufficient supply to cover the cans 16 passing through the machine.

The chute 69 is a gravity chute, and its lower portion is supported by a bracket 74 (see Figures 5, 7 and 9) on the machine frame, and this bracket carries a spring member 75 which is bent over as shown in Figure 9, and has its lower portion formed into a guard plate 75' which extends just above the filled cans and prevents the cans and their contents from being displaced.

Before further describing the operation of applying the covers, attention is called to the fact that after the cans leave the inner end of the carrier 11, they are pushed further along through the machine on spaced guide rails 76 which are suitably supported between the guides 15, their tops being substantially on the same level as the top of the carrier 11, and these rails serve the double purpose of permitting any dust or scattered material from the cans to drop through, and also of a solid support for the cans when pressure is applied to them in putting on the covers.

At the lower end of the cover delivery chute 69 and on the top thereof is a guide 77 which is held substantially parallel with

the bottom of the chute and serves to nicely guide the covers to place, this member being turned up slightly at its lower free end as shown at 78 in Figure 9. It can be supported in any convenient way, and I have shown it carried by cross bars 79 on the top of the chute. The member 77 is riveted to the upper cross bar 79 and can be adjusted up and down by a thumb screw 80 in the second cross bar so as to make it properly fit the covers.

The chute 69 is open at the under side as shown at 81 to permit the covers to drop through, and the sides of the chute are prolonged as shown at 69^a to assist in guiding the covers to place. At the lower end of the chute 69 and at the point where the covers are applied to the cans, is a pair of pawls 82 each pivoted as shown at 83 on the top sides of the chute, and the pawls are shaped to fit against the can covers, and are limited in their movements by the pins 83^b on the chute which enter the recesses 83^a in the pawls. The pawls are lightly pressed towards each other by a spring 84, and act like a pair of fingers to align the lowermost cover to the can beneath and guide the cover so that the same will first engage one edge of the can as shown clearly in Figure 9, and thus be properly started so that the continued movement of the can through the machine and the pressing down of the cover as presently described, will permit the latter to be surely adjusted; and to further facilitate this movement, the cover is guided as it descends and leaves the chute by a second pair of pawls 85 which are pivoted as shown at 86 on the sides of the chute, and have noses 87 pressing against the sides of the cover. The pressure is light, and is effected by the spring 88, all of which appears clearly in Figures 7 and 9.

As the cans and the covers which have now been started to place progress through the machine, the covers pass beneath a presser foot 89 (see Figure 9) the rear end of which is turned up as shown at 90 so as to easily engage the covers without denting them. This presser foot can be supported in any convenient way, and I have shown it hinged to a spindle 92 and pressed to place by a spring 91 arranged between the presser foot and a fixed collar 93 on the lower part of a hanger 94, the latter being supported from a bracket 95 (see Figures 8 and 9), and this has an arm 96 acting as a guide for the spindle 92, and the latter is further guided in the sleeve 94 arranged between the members 93 and 96. A nut 98 serves to hold the spindle in place.

The covers are now in place on the cans, and a final compression means is used to seat them firmly and securely for packing. This is accomplished by the rollers 99 and 100 (see Figure 6) which are vertically

spaced and are of comparatively large size so as to easily engage the cans without injury. The roller 100 is carried by a shaft 102, and the roller 99 by a shaft 101, the latter roller also working in an opening 103 in the rails 76 so as to contact with the bottom of the cans as they pass through. The direction of the rollers' rotation corresponds to the progressive movement of the cans so that the latter will pass freely through them, and it will be seen that every cover must be pressed securely to place, the lower edge pressing down to the bead 16.

The compression rollers 99 and 100 can be turned in any convenient manner. To show an operative means I have illustrated them as connecting by gears 104, and I have shown the shaft 102 provided with a sprocket wheel 105 driven by a chain 106 connecting with a sprocket wheel 107 on the shaft 108, and the latter connects by gears 109 and 110 with the driving shaft 24.

From the foregoing description it will be seen that I have produced a very positive and comparatively simple scheme for applying covers to filled cans with great accuracy and speed. It will be noted that the cans pass continuously without the necessity even of an intermittent movement through the guide of the machine, that the covers are automatically supplied to the delivery chute 69 in such a way that there is no danger of the covers missing, that the covers are accurately and automatically guided to their seats on the can tops as the latter pass beneath them, that the presser foot 89 serves simply by the movement of the cans themselves to press the covers to place, and that finally the compression rollers 99 and 100 force the covers to their final seats in a perfect and secure manner.

I claim:—

1. A machine of the kind described comprising means for moving a row of filled cans through the machine one behind the other, means for delivering covers successively to the cans so that each cover will first engage the corresponding edge portion of a can, and means for guiding and pushing the cover to its seat on the can, said means being actuated by the progressive movement of the can.

2. A machine of the kind described comprising means for moving a row of cans one behind the other through the machine, a delivery chute discharging individual covers upon the individual cans, a hopper supplying covers to the delivery chute, and means coacting with said covers to position the same in said chute whereby to guide the covers to the cans.

3. A machine of the kind described comprising means for feeding a row of cans one behind the other through the machine, means for shaping the cans symmetrically,

and means for applying covers to the cans while they are held in the shaping means.

4. A machine of the kind described comprising means for feeding a row of cans one behind the other through the machine, means for symmetrically shaping the cans as they pass through the machine, means for applying covers to the cans while held in the shaper, and means for finally forcing the covers to their seats on the cans. 75

5. A machine of the kind described comprising means for feeding a row of cans one behind the other through the machine, means for guiding covers to their seats on the cans as they pass through the machine, and spaced compression rollers arranged above and below the row of cans and adapted to engage the cans and move the same in the direction of travel and also to force the covers to their final seats as the cans pass 85 through them.

6. A machine of the kind described comprising means for feeding a row of cans one behind the other through the machine, shaping means for the cans, means for guiding the covers to their seats on the cans while the latter are in said shaping means, and a compression device exerting endwise pressure on the cans to force the covers to their final seats and to move the same in the direction of travel. 90

7. A machine of the kind described comprising means for feeding a row of cans one behind the other through the machine, a shaper comprising rotating members having 100 recesses to engage and symmetrically shape the cans as they pass through, and means for applying the covers to the cans while they are held in the shaper.

8. A machine of the kind described comprising means for feeding a row of cans one behind the other through the machine, and a shaper comprising a plurality of pairs of 110 rotating members to shape the cans as the latter pass between the said members and operative on a particular can as the cover is applied thereto.

9. A machine of the kind described comprising means for feeding a row of cans one behind the other through the machine, a delivery chute arranged to deliver covers to the cans, and guiding pawls near the junction of the chute and cans, said pawls being arranged to guide the covers to their seats on the cans. 115

10. A machine of the kind described comprising means for carrying a row of cans one behind the other through the machine, a guide chute delivering covers to the can tops, a pair of guide pawls arranged above the chute and in position to engage the covers and guide them so that their edge portions will engage the corresponding edge portions of the cans, and a second pair of pawls behind the first pair acting to guide 125 120 125 130

the covers as they are seated on the can tops.

11. A machine of the kind described comprising means for carrying cans one behind the other through the machine, a guide 5 chute delivering covers to the cans, means for aligning the individual covers with the individual cans as the cans pass the bottom of the chute, means for guiding the individual covers to the individual cans after said 10 covers have been aligned, and a presser foot above the can tops and in the path of the covers acting to push the covers upon the cans.

12. A machine of the kind described comprising means for feeding a row of cans one behind the other through the machine, a delivery chute arranged to deliver covers to the cans, flexible means for grasping the covers and guiding the same to the cans, 20 and a stationary presser foot arranged above the can tops and behind the cover guiding means whereby the forward movement of the cans will cause the presser foot to push the covers upon the cans.

13. In a machine of the kind described, the combination of means for carrying a row of cans one behind the other through the machine, a delivery chute arranged to deliver successive covers to the successive cans, a guide in the top of the chute, flexible guides on the sides of the chute arranged to align the covers with the cans, and flexible guides on said chute to engage the covers after alignment and guide the same to 30 their seats on the cans.

14. A machine of the kind described comprising a horizontally moving carrier for cans, spaced rails forming an extension of the carrier, and means for applying covers to the cans while the cans are on the said 40 rails.

15. A machine of the kind described comprising a carrier moving in substantially a straight line, spaced rails forming an extension of the carrier, and means for applying covers to the cans and pressing the covers to place while the cans are on the said rails.

16. A machine of the kind described comprising means for moving a row of cans one behind the other through the machine, a delivery chute to discharge the covers upon the cans, a guide on the top of the chute at the point where the chute discharges the covers, and a presser foot forming an extension of said guide and arranged to push the covers upon the cans.

17. A machine of the kind described comprising means for moving a row of cans through the machine, means for delivering covers to the cans with the rear edges of the covers first engaging the cans, and a yielding presser foot arranged substantially opposite the end of the cover delivering means and adapted to push the covers upon the cans and spaced above the cans and in

line with the partly raised cover tops, said presser foot having its front portion rounded at the point where it strikes the cover.

18. A machine of the kind described, comprising in combination with means for feeding cans one behind the other through the machine a cover supplying means comprising a delivery chute, a hopper for carrying covers, means for raising the covers from the hopper to the mouth of the delivery 75 chute, and a jet pipe arranged to blow the covers from the carrier to the chute.

19. A machine of the kind described, comprising in combination with means for feeding cans one behind the other through 80 the machine a cover supplying means comprising a cover delivery chute, a hopper, a carrier movable through the hopper and arranged to raise covers to the mouth of the delivery chute, means for blowing the covers from the top of the carrier into the chute, and guides opposite the cover carrier acting to center the covers on the carrier and to brush off improperly placed 85 covers.

20. A machine of the kind described, comprising in combination with means for feeding cans one behind the other through the machine, a cover delivery means comprising a hopper, a cover delivery chute, a carrier 95 arranged to raise covers from the hopper to the delivery chute, a second chute through which the carrier runs, said second chute discharging into the hopper and having a width permitting covers to lie between the 100 side of the chute and the carrier, and means for brushing improperly placed covers from the carrier to the said second chute.

21. A machine of the kind described, comprising in combination with means for feeding cans one behind the other through the machine a cover delivery means comprising a hopper, a cover delivery chute, a carrier to raise the covers from the hopper to the chute, a jet pipe to blow a portion of the 105 covers from the carrier to the delivery chute, and means for returning the blown covers to the hopper.

22. A machine of the kind described comprising in combination with means for feeding cans one behind the other through the machine, a cover delivery means comprising a hopper, a delivery chute, a carrier to raise the covers from the hopper to the delivery 110 chute, a second chute leading to the hopper, a jet pipe to blow a portion of the covers from the carrier to the delivery chute but permitting the remainder to return to said hopper through said second chute, and means for returning certain of the blown 120 covers to the hopper.

23. A machine of the kind described, comprising in combination with means for feeding cans one behind the other through the machine a cover delivery means comprising 125

- 8
- a delivery chute, a hopper, a carrier arranged to carry an excess supply of covers to the delivery chute with some of the covers top side up and the others bottom side up, and a jet pipe directed and arranged to blow the covers which are bottom side up into the said delivery chute.
24. A machine of the kind described, comprising in combination with means for feeding cans one behind the other through the machine a cover delivery means comprising a delivery chute, a hopper, a carrier arranged to carry an excess supply of covers to the mouth of the delivery chute, a second chute near the mouth of the delivery chute and extending back to the hopper, means for discharging the excess cover supply to the second or return chute and means for returning some of the covers from the delivery chute to the hopper.
25. A machine of the kind described, comprising in combination with means for feeding cans one behind the other through the machine a cover supply means comprising a hopper, a delivery chute, means for raising an excess supply of covers to the mouth of the delivery chute, means for blowing the covers which are bottom side up into the delivery chute, a second chute arranged to return the unblown covers back to the hopper, and means for discharging the excess covers from the side of the delivery chute into the said second chute.
26. A machine of the kind described, comprising in combination with means for feeding cans one behind the other through the machine a cover delivery means comprising a chute of a width to guide the covers and with a side opening therein, means for delivering an excess number of covers in the mouth of the chute whereby the surplus or excess covers will pass out through the aforesaid side opening and means permitting only a portion of the covers to be delivered to the delivery chute.
27. A machine of the kind described, comprising in combination with means for feeding cans one behind the other through the machine a cover delivery means comprising a chute to deliver covers having its main portion of substantially the width of the covers and with a side opening therein, a hopper, a carrier to raise the covers from the hopper to the mouth of the delivery chute, means for carrying an excess number of covers from the carrier to the mouth of the delivery chute, and a return chute connecting with the said side opening of the delivery chute and arranged to return the excess covers back to the hopper.
28. A machine for applying covers to cans comprising means for carrying the cans one behind the other row-wise through the machine, a cover delivery chute arranged to deliver the covers to the cans with the back edges of the covers first engaging the corresponding edge portions of the cans, means operated by the progressive movement of the cans to seat the covers on the cans, a cover supply hopper, means for delivering covers to the delivery chute from the hopper in excess of the number required to load the delivery chute, and means for returning the excess number of covers to the hopper.
29. A machine of the kind described comprising means for feeding cans through the machine a cover delivery means comprising a cover hopper, a chute delivering covers, a carrier raising the covers from the hopper to the chute, means for discharging a portion of the covers from the carrier to the chute, means for returning the remaining covers to the hopper, an agitator in the hopper comprising movable belts running adjacent the walls of the hopper, and means to seat the covers on the cans.

In testimony whereof, I have signed my name to this specification this 26th day of June, 1925.

CHARLES O. ERICSON.
